A. C. Fischer
Inventor:

UNITED STATES PATENT OFFICE.

ALBERT C. FISCHER, OF CHICAGO, ILLINOIS.

EXPANSION-JOINT SECTION.

Application filed October 19, 1925. Serial No. 63,363.

My present invention relates in general to expansion joints for concrete and the like constructions, and has particular reference to a preformed expansion joint constructed of sectional strips, with the sections of the strips provided with means for uniting the same end to end so that the joint may be installed in lengths suitable for the purpose to which it is to be applied, and with the ends connected so as to tightly close the same against the possibility of concrete or other foreign material collecting between the abutting ends of the sections and destroying the effectiveness of the joint.

15 Two forms of the invention are shown in the accompanying drawing by way of illustration, in which Figure 1 is a perspective view of one form of the invention; Figure 2 a detailed plan view of the form shown 20 in Figure 1; Figure 3 is a view in side elevation of another form of the invention and Figure 4 is a similar view showing the sections constructed as in Figure 3 connected.

Referring now to the drawing in detail A 25 and B represent two sectional strips of expansion joint, which may be made of a proper thickness and in a suitable length, with the same sections adapted to be connected together so as to offer a continuous strip when installed as a joint.

In all forms of the invention I prefer to equip the sections of this strip with overlapping projections so as to realize an effective connecting means for the sections. In one 35 form these interlocking projections are to be realized by providing a rabbeted edge —5— on the ends of each section, so as to leave projections —6—. The recess made by the rabbeted edge —5— and the projection —6— will produce a complementary overlap of the section ends, so that the interlocking projection —6— on one section will fit the recess made by the rabbeted edge —5— on an abutting section. With this interlocking arrangement, as best shown in 40 Figure 1, a snug fit may be made between the abutting ends of the sections, and the interlocking projection —6— will securely hold the sections together, particularly when the concrete is poured around the same.

In Figure 3 I have shown another form of interlocking projections in the form of a morticed joint. In this form the projections

—7— on the ends of one section will fit the recesses —8— on an adjacent section, and the adjacent section is made with an intermediate interlocking projection —9— which is adapted to fit the recesses —10— between the projection —7—. In this form when the sections are joined together, as shown in Figure 4, a pin or the like —11— may be driven down thru the joint so as to lock the projections —7— in the recesses —8—, and the projection —9— in the recess —10—.

In all forms the interlocking and overlapping projections offer a more convenient and effective means of connecting the sections together for the reasons above indicated.

It might be stated here that the material from which the joint is constructed will ordinarily comprise a mixture of blown bituminous material or the like, and a filling material such as, fibrous matter. This is simply mentioned so that it will be readily appreciated how the cuts can be made to produce these interlocking projections.

I claim:

1. A preformed expansion joint of bituminous material, wherein the opposite edges are provided with alternate cut-outs and projections of sufficient depth to provide interlocking flanges when the ends of two such joints are interconnected, said cut-outs and projections extending throughout the height of the strip; and a fastening pin adapted to pass thru a plane parallel with the height of the strip and thru the interlocking portions to hold adjacent ends of the strip together.

2. A preformed expansion joint composed of bituminous material, the opposed ends of the joint having relatively deep cut-outs and projections adapted to receive similar cut-outs and projections of a connectible strip, and a fastening pin passing transversely thru the interlocking projections of two such interconnected strips whereby to hold them in assembled relation.

3. A relatively thin, preformed expansion joint of substantial height or width, adapted to be installed so that the plane of its width is in substantially vertical position, said joint being formed of non-metallic compressible and expandable material, and said joint having its opposite ends provided with cut-outs and tongues extending longitudi-

nally of the height of the strip, the cut-outs on one end being positioned opposite the tongues of the opposite end and being constructed and arranged so that the end of one strip will overlappingly interlock with the opposite end of another strip; and a relatively long pin adapted to pass through said

tongues and cut-outs, so as to hold the overlapped ends of adjacent strips in locked relation.

In testimony whereof I have signed my name to this specification, on this 8th day of October, A. D. 1925.

ALBERT C. FISCHER
